UNITED STATES PATENT OFFICE.

GREENLEAF WHITTIER PICKARD, OF AMESBURY, MASSACHUSETTS.

ELECTRICAL CONDENSER.

No. 893,811.

Specification of Letters Patent.

Patented July 21, 1908.

Application filed November 5, 1907. Serial No. 400,777.

To all whom it may concern:

Be it known that I, GREENLEAF WHITTIER PICKARD, a citizen of the United States of America, and a resident of Amesbury, Massachusetts, have invented certain new and useful Improvements in Electrical Condensers, the principles of which are set forth in the following specification and accompanying drawing, which disclose the form of the invention which I now consider to be the best of the various forms in which said principles may be embodied.

This invention relates to electrical capacities or condensers, particularly those used with high-potential currents, as in wireless telegraphy and telephony, the object being to make them more durable and efficient; and the invention consists in the disclosure hereinafter set forth in detail, the object 20 being to prolong the life of such condensers, and to prevent localized heating and destruction due to a blistering or separation between the conducting coating and the dielectric material to which said coating is attached.

Figure 1 is a diagrammatic illustration of the product of the first step in the manufacture of the invention; Fig. 2 a similar illustration of the execution of the second step; and Fig. 3 an illustration of the product of 30 the second step, this being the final product.

In the art of wireless communication, all condensers employing solid dielectrics have heretofore in use been vitally defective and short-lived, owing to the action consequent upon the presence of blisters between the conductor and the dielectric material. When the condensers were subjected to the high potential, high frequency currents of this art, more or less extensive blistering occurred, and the electrical discharges occurring between the conducting coating and the surface of the dielectric, across the gaseous medium within such blisters, heated the dielectric in the immediate neighborhood to such a degree as not only to greatly reduce the efficiency of the device, but to shortly destroy it. This has resulted, since condensers are essential in the practice of this art, in making the condenser a very weak point in telegraphy transmitting installations, particularly in the case of ships or installations where replacements could not be made within a short period. It had been supposed that this deleterious action was due chiefly to the intervention and retention of air bubbles or moisture during the process of pasting the

conducting tin-foil coating to the glass dielectric material, which resulted in minute air or moisture-filled pockets between the two, and a consequent discontinuity of contact 60 which resulted in localized heating. In accordance with this hypothesis, it has been the practice to exercise great care in so applying the tin-foil coating as to have it make good continuous contact with the dielectric 65 material so as to avoid the intervention and retention of air-bubbles or concentrated excess of the solvent of the cement employed to affix the tin-foil to the dielectric material. Frequently the practice has been to there- 70 after subject the device to a baking heat to remove as much as possible of the confined gases and solvents. It has also been proposed, as in United States Patent No. 814,951, to so construct and apply the con- 75 ducting coating as to leave holes or openings in it, so that when the device was subjected to the baking process, the confined air, etc., might the more readily escape or be removed, as through such openings. In practice, how- 80 ever, none of these expedients has prevented the evils enumerated above. I have investigated this serious question, and have found that the trouble is not chiefly due to the causes heretofore contemplated, but, as I 85 have discovered, the chief cause is that the action of the high potential currents is not only such as to cause undue heating at blistered points, but to itself cause the production of such blisters, after the manufacture of the 90 device is completed and the same put into use. That is to say, no matter how great care is exercised during manufacture, to exclude the air or excess of moisture, the action of the currents is such as to liberate, after the 95 device is put into use, additional gases, which produce blisters, a resulting discontinuity of contact, and the consequent localized heating, impairment, and final de- 100 struction. I have further observed that the action of the currents, during the use of the device, in liberating gases causing blistering, is due simply to the manufacturing practice of using either as the dielectric base or as the cement or both, materials which were of such 105 nature as to provide a source for the production of gases by the action of the currents. Thus, hard rubber, or similar organic material, has often been used as the dielectric base, and in all cases the cement or binder 110 has consisted of a solution of shellac or other material containing either a solvent or or-

ganic matter, or both, constituting a source of gases made prolific by the action of the high potential currents.

In accordance with this invention, which reaches the heart of the difficulty, the cement or binder, and in fact the entire device, is constructed of such materials, that, while preserving the proper materials and functions of the dielectric base and conducting coating, none of the materials can constitute a source of blister-producing gases under the action of the currents employed in the use of the device for wireless communication. I have demonstrated by long-continued trials, that it is possible to produce a condenser, with such admirably adapted materials as glass for the dielectric base, and a metal for the conducting coating, and with a binder lacking in organic matter, moisture, solvents or other gas-yielding components which might cause blistering in the best form of the invention, which condenser will have its parts permanently secured together as a whole and in permanent closé contact at all points. I have proved that such a condenser not only executes all the desired functions of previous condensers, but also obviates all the troubles with the latter.

Various materials may be employed as the binder, in pursuance of this invention, including those which are self-hardening and setting. For example, there may be employed any of the so-called hydraulic cements, such as the dental cement known in trade as "Petroid". When glass is used as the dielectric base, I prefer to use the silicate cement known as soluble glass, and called also mineral lime, and also "water glass", owing to its solubility in hot water. Most of such binders, in order to be non-gas-producing, are inorganic and are lacking in solvents which might produce excessive amounts of gas under the conditions of use. They are to be applied to the dielectric base by a brush or by immersing the base in a bath of the binder. While the binder is in a soft condition on the base, the conducting coating, which may be tin-foil, is to be applied, so that when the binder sets or hardens, either with or without baking, the conductor will be firmly attached to the base.

One of the classes of binders included within the invention is that which is itself of a metallic or conducting nature, or otherwise suitable for an electrolytic deposit of an electrically conducting material, in addition to its property of being itself permanently attachable to the base; or that which itself performs the function not only of a binder, but of a conducting coating; all such being substantially inorganic in composition. An example of this is a coating comprising a metallic paint consisting of a powdered conductor, such as graphite or bronze powder and silicate of sodium, or potash, ("water

glass") in aqueous solution, this being particularly well adapted for use with a glass dielectric base owing to the attachability of the glass binder to the glass base. In any case, the metal, (bronze or graphite, etc.,) is ground exceedingly fine, and when sufficiently fine and when the paint solution is not too fluid, and the coat applied is sufficiently thick, this coating may suffice as the only conducting coating. In any case, the mineral lime or "water glass", when applied and set upon the glass base, serves as a means of permanent attachment to and incorporation with the glass; and the metallic paint, when hardened, serves as an admirable base for the electrolytic deposition of a suitably thick or thin metallic conducting coating, which may be desirable or necessary when the metallic paint alone is unsuitable for use as the complete conductor coating. After the metallic paint is attached to the glass base, as by its silicate constituent, an electrolytic deposit may be made on it of any desirable thickness, such as to insure against blistering or puncturing.

In Fig. 1, J is a jar which may be glass, and P the coating of binder or paint, which may be applied by a brush or by immersion of plate J in a bath of the binder. (When the simple mineral lime binder is used, the metallic conductor is smoothly laid over it in the form of sheets, such as tin-foil, and the product baked. In this case, as in the case where metallic silicate paint alone constitutes a sufficient conducting coating, no electrolytic deposit need be made. (The silicate element of the metallic paint may be a silicate of sodium solution in water, the strength of the solution being such as to give a syrupy consistency to the paint, not necessarily too thick, however, as not to be easily spread on the glass base by the brush. Two sides of the glass will be treated in accordance with the invention, to produce a complete condenser. The jar J of course may be replaced by a plate or other suitable form, the art now employing both plate and jar condensers. After the paint or binder P is applied, the elements J and P together are baked in an oven. If sodium or potash silicate solution is employed, the time of such plating may advantageously be about an hour. The temperature of the oven during this step about one hundred degrees centigrade.

After the step of baking, the conducting element of the coating may be reinforced by an electrolytic deposit thereon, the metallic element of the paint serving as a base for the deposit. As in Fig. 2, the baked product J, P may be placed in a bath B in a tank T suitably insulated. The plating bath may be copper sulfate solution. The metallic silicate coating P (the two separate coatings P, P being connected by a lead D) is con-

nected by lead L to one terminal of a suitable electric generator E, the other terminal M being connected to one anode A (or anodes A, A¹ and A²) in the bath B. The size of the individual anodes and their distribution with respect to the surfaces to be heated, affords a constant and uniform deposit on all such surfaces. This step is facilitated by a relative movement of the condenser and anode, which may be obtained by rotating the former with respect to the latter. As shown, two wooden disks F, G, internally applied to the condenser to support it in bath B, are mounted on a rod H which is rotated at any desired speed by the application of power to the ground pulley W. The plating operation may continue until any desired thickness of plating is produced, as at C, Fig. 3. This is simply a question of economy. The plating is sufficient to absolutely insure against blistering at the high temperature of use, even if it be but of slight thickness, just sufficient to form a complete coating over the metallic paint.

25 The product, shown in Fig. 3, comprises a good conducting coating C which will not blister or deteriorate in use, and which is firmly attached to the base J, by being incorporated with the metal powder in the paint P, that powder being held firmly by its associated hardened silicate, and that silicate being firmly attached to the like material, glass, of which J is composed.

I claim:

35 1. A condenser consisting of a dielectric base, in combination with a conducting coating, and a composite paint between said elements and having an inorganic substance as one of its constituents and combined with the base and another and conducting metallic constituent combined with the conducting coating.

2. A condenser consisting of a glass base, a silicate binder incorporated with said base, 45 and a conducting coating incorporated with said binder.

3. A condenser consisting of a glass base, a silicate metallic cement, and an electrolytic deposit of a conducting coating combined with the metallic element of the cement.

50 4. An electrical condenser, which consists of a glass base, and a surface coating of a conducting paint incorporated into the material of said base.

5. A condenser comprising a dielectric base, a binder on the base and having a finely-

60 powdered conductor admixed with it, and an electrolytic deposit of a conducting coating combined with the conducting constituent of the binder.

6. A condenser comprising a dielectric base, an inorganic binder on the base and having finely powdered metal admixed with it, and an electrolytic deposit of a conducting coating combined with the metal.

65 7. A condenser comprising a glass base, a paint thereon consisting of a mixture of mineral lime and finely-powdered metal, and a metallic electrolytic deposit combined with said metal.

70 8. The method of producing electrical condensers, which consists in applying a coating of conducting paint upon the surface of a glass base, and then subjecting the glass base with the metallic paint applied, to a high degree of heat.

80 9. The method of producing condensers, which consists in applying a cement of mineral lime and finely-powdered metal on a glass plate, baking the same, and then electrolytically producing a metallic deposit upon the cement.

90 10. The method of producing electrical condensers, which consists in applying a coating of conducting paint upon the surface of a glass base, then subjecting the glass base with the metallic paint applied, to a high degree of heat, and then electrolytically producing a deposit of a metal upon the incorporated conducting paint.

11. An electrical condenser, which consists of a glass base, a binder incorporated with said base, and an electrical conductor incorporated with said binder.

95 12. A condenser comprising a glass base, and a paint thereon consisting of mineral lime and of a finely powdered metallic conductor.

13. A condenser comprising a glass base, a paint thereon containing mineral lime containing a finely powdered metallic conductor, and an electrolytic deposit of a metal combined with said powdered conductor.

100 14. A condenser comprising a glass base, a conducting paint thereon, and an electrolytic deposit of a conductor combined with the conducting paint.
